(57) **CLAIM**

The ornamental design for a bottle cooler, as shown and described.

DESCRIPTION

FIG. 1 is a front perspective view of a bottle cooler showing my new design;

FIG. 2 is a top plan view thereof;

FIG. 3 is rear elevational view thereof;

FIG. 4 is a right side elevational view thereof;

FIG. 5 is a bottom plan view thereof; and,

FIG. 6 is a front perspective view shown in use thereof.

The short dash lines shown in FIGS. 1, 3, and 6 of the bottle cooler represents stitching lines and are part of the claimed design.

The long dash lines shown in FIG. 6 of the bottle cooler are for the purpose of illustrating environment, and forms no part of the claimed design.

1 Claim, 3 Drawing Sheets
